UNITED STATES PATENT OFFICE.

WALTER E. BARNARD, OF HARTFORD, CONNECTICUT, ASSIGNOR TO UNDERWOOD
TYPEWRITER COMPANY, OF NEW YORK, N. Y., A CORPORATION OF DELAWARE.

TYPE-WRITING MACHINE.

1,073,068.

Specification of Letters Patent. Patented Sept. 9, 1913.

Application filed June 21, 1912. Serial No. 704,975.

To all whom it may concern:

Be it known that I, WALTER E. BARNARD, a citizen of the United States, residing in Hartford, in the county of Hartford and State of Connecticut, have invented certain new and useful Improvements in Type-Writing Machines, of which the following is a specification.

This invention relates to a combined decimal tabulator and column finder for a type-writing machine.

In certain typewriting machines such as the Underwood, decimal tabulating mechanism is provided for selecting or arriving at any point such as a decimal place in a given column, that is to say, the position of the carriage is controlled to bring to the printing point any desired letter space in a given column.

It is the purpose of this invention to use certain parts of this decimal tabulating mechanism to find or locate any one of a number of columns. That is to say, arrangement is made whereby certain keys can be used alternatively for either decimal tabulating or column finding.

In the mechanism in connection with which this invention is illustrated, decimal tabulating keys are arranged to move decimal or counter stops shown in the form of plungers, into the path of column stops carried by the carriage, and at the same time release the carriage for forward movement under the traction of its spring barrel. In this improvement a special key is provided, which, when depressed, forces the counter stops to an ineffective position out of the path of the column stops, leaving them free to move without interrupting the movement of the carriage. The actuation of this key also tensions a spring connected to the initial counter stop so as to tend to draw it to an effective position. A latch, however, prevents the movement of this stop until a

trip which is provided therefor releases it. The trip is movable variable distances so that it may be actuated by any one of the different column or carriage stops which have shoulders of increasing lengths from left to right of the carriage. The rocking of the trip to set the same is governed by a stepped lever, which is moved variable distances by lugs on certain of the plungers actuated by certain of the decimal tabulating keys.

Other features and advantages will hereinafter appear.

In the accompanying drawings, Figure 1 is a fragmentary perspective view looking at the rear of the combined decimal tabulating and column finding mechanism. Fig. 2 is a diagrammatic view, showing the co-operation of the trip with the successive stops having shoulders of graded magnitudes. Fig. 3 is a diagrammatic section taken from front to rear of the machine. Fig. 4 is a fragmentary top plan view, partly in section, of the tabulating keys and their connection with the carriage controlling mechanism. Fig. 5 is a detail view in vertical section, showing the special control key depressed, so as to bring all of the counter stops or plungers to their ineffective position. Fig. 6 is a view similar to Fig. 5, showing the parts in the same position, with the exception that one of the tabulating keys has been actuated to bring the trip into the path of movement of one of the carriage or column stops. Fig. 7 is a view of the parts shown in Figs. 5 and 6, showing the trip after it has been actuated by the column stop so as to release the latch holding the initial counter stop in its ineffective position, so that the spring has been permitted to draw this counter stop into the path of movement of the carriage or column stop which has actuated the trip.

Referring more particularly to the separate parts of this invention as embodied in the form shown in the drawings, 1 indicates the keys which actuate through the intermediary of bell cranks 2 type bars 3, to swing the latter rearwardly against the front side of a platen 4 carried by a carriage 5. The carriage 5 has a spring barrel 6 connected thereto, to tend to move it forward in a letter-feeding direction under the control of an escapement mechanism which includes a universal frame 7 actuated by a heel 8 on each of the type bars 3, so as to rock a pair of pawls 9 to control the movement of an escapement wheel 10. The escapement wheel 10 is connected with a pinion 11, which meshes with a rack 12 carried by arms 13, which are pivotally mounted on the carriage 5.

In addition to the step-by-step movement of the carriage, there may also be provided a jump movement of the carriage to quickly bring different parts of the carriage to the

printing point. For this purpose, there may be provided a series of decimal tabulating keys 14, which are provided with levers 15 pivotally mounted intermediate their ends 5 as at 16, and underlying at their rear ends a series of counter stops 17, shown in the form of plungers adapted to be brought up into the path of movement of a series of column stops 18, adjustably mounted on a 10 rack 19 carried by the carriage 5. Each of the plungers or counter stops 17 has a cut-out portion as at 20, to form a shelf for a universal lever 21, whereby when any one of the tabulating keys is actuated, this lever 15 will be rocked. The lever 21 is connected to draw down on a link 22, which is arranged to rock a lever 23 carrying at its forward end a roller 24, which bears on the under surface of a smooth portion of 20 the rack bar 12, so that when any one of the tabulating keys is actuated, the rack 12 will be moved out of mesh with the gear 11, permitting the carriage 5 to run forward freely until the actuated counter stop 17 25 comes into the path of the carriage or column stop 18 next to the right of the nest of plungers 17. It will be seen by this arrangement that any decimal place or letter-space in a given column can be brought to 30 the printing point by a manipulation of the proper tabulating key 14. In addition to this selection of a particular letter space in a given column, it is often of value for quick work, to enable the operator to select 35 any particular column, and bring the carriage so that this column will come to the printing point. In this instance, certain of the same tabulating keys which control the selection of any particular letter space in a 40 given column, are used to control the selection of any column. To accomplish this, certain of the tabulating keys indicated at 25, of which there are four, shown in this instance corresponding to four columns to 45 which it is possible to jump, are utilized to control a column finding mechanism. In order that the columns to which these keys correspond may be readily ascertained, there is provided an indicating plate 26 in close 50 juxtaposition thereto, indicating the several columns by numbers "1" to "4". These keys 25, therefore, are both decimal tabulating keys and column finding keys.

For the purpose of changing the function 55 of the keys 25 from decimal tabulating keys to column finding keys, there is provided a special control key 27, which is provided with a lever 28 pivoted intermediate its ends and having a slotted connection with the 60 pivot 16 of the levers 15, so as to be capable of moving relative thereto at this point. The rear end of the lever 28 underlies a plunger or thrust link 29, so as to raise it, thereby swinging a rocker or bell crank 30 65 about its pivot. Rocker 30 has rearwardly

extending arms 31 on which is mounted a shifting rod 32 extending through aligned slots 33, provided in all of the plungers or counter stops 17 with the exception of the initial plunger or counter stop which is 70 specially indicated at 34. By this arrangement it will be seen that when the special control key 27 is actuated, rod 32 will draw all but one of the plungers or counter stops 17 forward, so as to bring their upper ends 75 out of subjacent relation with respect to the column stops 18, permitting the counter stops to move upwardly without coming into the path of any of the column stops 18.

In order to bring the initial counter stop 80 34 forward to an ineffective position, there is pivotally connected to the rocker 30 a latch 35 having an upstanding lug 36 engaging a pin 37 on the counter stop or plunger 34. The latch 35 moves with the rocker 85 30, so that it swings the initial counter stop or plunger 34 to its ineffective position at the same time that the other counter stops are swung out of active relation with respect to the stops 18. The forward movement of the initial counter stop 34 tensions a spring 38 which is connected thereto, so that this spring will tend to return the counter stop 34 when the latch 35 is released.

For the purpose of releasing the latch 35, 95 there is provided a trip 39 having a pin and slot support 40, so that it is capable of rocking motion and also of vertical motion. The trip, however, is normally held in its upper and rearward position by means of a spring 100 41. The trip 39 has an arm 42 bent at right angles to the body portion to overlie an extension 43 of the latch 35, whereby when the trip is depressed, the latch 35 will be moved downwardly to permit the counter stop 34 105 to swing back to its rearward position. The lug 36 of the latch 35, however, is provided with an upwardly and rearwardly inclined cam edge 44, so that the spring 38 will not only swing the counter stop 34 rearwardly, 110 but will also bring it up into the path of the column stop 18 which is moving toward it. The trip 39 is itself actuated to depress the latch 35 by the column stops 18, each 115 of which is provided with a shoulder 45. As will be seen by reference to Figs. 2 and 3, the shoulders are of different lengths, increasing in length from left to right of the carriage; that is to say, the stops 18 have a graded obstructing effect which increases 120 from left to right of the carriage, so that the trip 39 can be swung from a position out of cooperation with all of the stops, to a position into cooperation with any one of the stops, depending upon the extent of 125 its movement in swinging.

To set the trip 39 so that it will be actuated by any certain one of the column stops 18, there is provided a lever 46 (see Fig. 1), 130 which is located in such a position that it

will be actuated by any one of the plungers or counter stops 17, corresponding to the tabulating keys 25, when they are in their ineffective position. When these particular counter stops or plungers 17 are in their ineffective position, lugs 47 underlie the bottom of the lever 46, so that when any one of the counter stops corresponding to the keys 25, is raised the lever will also be raised an amount depending upon the distance of the lug on the raised counter stop from the pivot of the lever 46, and also depending on a series of steps 48 provided on the engaging edge of the lever 46. Lugs 47, however, are spaced apart at their top edges from the body portion of the counter stops 17, so that when these counter stops 17 are in their effective positions, capable of engaging with the column stops 18, the cut-out portions thus formed will be in register with the lever 46, so that the counter stops can be raised without affecting the lever. The lever 46 when raised against the tension of the spring 41, which is also connected thereto, engages a cam edge 49 provided on the trip 39, so that the trip 39 is swung to the left (see Fig. 7) a variable amount according to the particular one of the decimal tabulating and column finding keys 25 which is actuated. If the first indicated by the numeral "1" is actuated, the trip 39 will be swung a maximum distance, bringing it into the path of the shortest shoulder 45, which is carried by the stop 18 which is farthest to the left on the carriage 5. The other keys 25 will swing the trip 39 in decreasing amounts to coöperate with the larger shoulders on the succeeding stops 18. In other words, the trip is projected inwardly the least amount to stop the carriage corresponding to the column located farthest to the right, to avoid the other stops 18, and in successively increasing amounts to catch the successive stops and avoid those located in front thereof. The upper edge of the trip 39 is guided in a slot 50 which permits a vertical and swinging movement of the trip 39, but prevents a movement in the direction of the length of the carriage, so that a cam surface 51 on the trip, when engaged by one of the stops 18, will act to depress the trip against the tension of the spring 41, so as to release the latch 35.

In the use of the device, if it is desired to position the carriage to bring any letter space of a given column in opposition to the printing point, the corresponding key 14, 25 is depressed, so that the associated counter stop 17 will be brought up into the path of the carriage stop 18, which happens to be to the right of the manipulated counter stop. When it is desired to skip a number of columns, or in other words to find any particular column, the key 27 is first depressed and held in its depressed position until one

of the keys 25 is depressed. The movement of the key 27 shifts all of the counter stops 17 to the position shown in Fig. 5, where they are all rendered ineffective to interrupt the movement of the stops 18. The counter stop 34, however, is only held forward by the latch 35, and the spring 38 is always tending to return the counter stop 34 to its effective position. As soon as one of the keys 25 is actuated, it lifts the corresponding counter stop 17, so that the lug 47 thereon which was ineffective when the counter stops occupied their normal position, will now engage the lever 46 to raise it such an amount as will bring the upper end of the trip 39 into the path of movement of the shoulder 45 on the proper column stop 18. The trip 39, however, will not be moved forward far enough to engage the shoulders 45 of such of the column stops 18 as may be located in advance of the proper column stop for a particular key 25 depressed. As soon as the column stop 18 engages the trip 39, it acts against the cam edge 51 to depress it, whereby the trip in turn, releases the latch 35, permitting the spring 38 to draw the counter stop 34 rearwardly and upwardly along the cam edge 44, in time to bring the top end of the counter stop in the path of movement of the particular column stop 18 which depressed the trip 39. The keys 27 and 25 can then be released, and the parts will assume a normal position with the counter stops 17 in a position capable of acting to locate the carriage in a position corresponding to any letter space in a given column.

Variations may be resorted to within the scope of the invention, and portions of the improvements may be used without others.

Having thus described my invention, I claim:

1. The combination with a carriage, of a series of column stops carried by said carriage, a series of counter stops, any one of which can be brought into engagement with any of said column stops to position said carriage in any decimal place in a given column, and means for bringing a certain one of said counter stops into engagement with any one of said column stops, to position said carriage for any one of a number of columns.

2. The combination with a carriage, of a series of column stops, a series of counter stops coöoperating with said column stops to determine the position of said carriage, a key, means operated thereby to hold one set of said stops in ineffective position, and a trip device operated by the counter stops to release a stop of said set and permit it to move to effective position.

3. The combination with a carriage, of a series of column stops, a series of counter stops coöoperating with said column stops to

4. The combination with a carriage, of a series of column stops, a series of counter stops coöperating with said column stops to determine the position of said carriage, means for rendering one set of said stops ineffective while the other set remains effective, and selective means to enable one of the ineffective stops to oppose any selected stop of the effective series.
5. The combination with a carriage, of a series of column stops, a series of counter stops coöperating with said column stops to determine the position of said carriage, means for rendering one set of said stops ineffective while the other set remains effective, a spring tending to return one of said ineffective stops to interrupt one of said effective stops, and means for determining which of said effective stops shall be interrupted.
6. The combination with a carriage, of a series of column stops, a series of counter stops coöperating with said column stops to determine the position of said carriage, means for rendering one set of stops ineffective while the other set remains effective, a spring tending to return one of said ineffective stops to an effective position, a latch for preventing the return of said last-mentioned stop, and a trip for releasing said latch.
7. The combination with a carriage, of a series of column stops, a series of counter stops coöperating with said column stops to determine the position of said carriage, means for rendering one set of stops ineffective while the other set remains effective, a spring tending to return one of said ineffective stops to an effective position, a latch for preventing the return of said last-mentioned stop, and a trip for releasing said latch, said column stops having shoulders of graded magnitudes to severally coöperate with said trip at different positions thereof.
8. The combination with a carriage, of a series of column stops, a series of counter stops coöperating with said column stops to determine the position of said carriage, means for rendering one set of stops ineffective while the other set remains effective, and selective means to enable one of the ineffective stops to oppose any selected stop of the effective series, said selective means being ineffective when both of said stops are in their effective positions.
9. The combination with a carriage, of a series of stops carried by said carriage, a plurality of tabulating keys, plungers actuated by said tabulating keys in such a manner that any one of said plungers may come into the path of the stop on said carriage next to the right of the series of plungers, to determine the position of said carriage corresponding to any desired letter space in a certain column, means for moving said plungers to an ineffective position, and selective mechanism controlled by certain of said keys to bring a certain one of said plungers into stopping relation with any one of said stops, so as to determine the position of said carriage corresponding to any desired column.
10. The combination with a carriage, of a series of stops carried by said carriage, a plurality of tabulating keys, plungers actuatable by said tabulating keys to move into the path of said stops to determine any position of said carriage corresponding to any desired letter space in a given column, a special control key, connections between said control key and said plungers whereby said plungers will be moved to an ineffective position when said control key is actuated, and selective means actuatable when said control key is depressed by any one of certain of said tabulating keys to bring one of said plungers into the path of movement of the stop on the carriage corresponding to the particular tabulating key actuated.
11. The combination with a carriage, of a series of stops carried by said carriage, a series of tabulating keys, plungers actuatable by said tabulating keys to move into the path of said stops, a bar connected to certain of said plungers, a control key for moving said bar so as to affect the operative relation of said plungers with respect to said stops, and means to enable certain of said tabulating keys to bring a plunger into stopping relation with any one of said stops when said control key is depressed.
12. The combination with a carriage, of a series of stops carried by said carriage, a series of contour stops to coöperate with said carriage, stops for the purpose of controlling the position of said carriage, tabulating keys for actuating said plungers, a control key, means actuated by said control key to positively move all but one of said counter stops to an ineffective position, a latch for moving the remaining one of said counter stops to an ineffective position, a spring connected to said remaining counter stop tending to return it to an effective position, a trip for releasing said latch, and means for selectively positioning said trip so as to be selectively operated by any desired one of said carriage stops, said last-

mentioned means being controllable by certain of said tabulating keys.

13. The combination with a carriage, of a series of column stops carried by said carriage, a plurality of tabulating keys, a series of counter stops movable by said tabulating keys into the path of said column stops, a control key for determining the effective relation of said two series of stops, certain 10 of said counter stops having openings extending therethrough, a rod actuated by said control key extending through said openings, a pin on one of said counter stops, a latch actuatable concomitantly with said rod 15 by said control key engaging said pin to move the counter stop on which it is located concomitantly with the movement of the other column stops, a spring tensioned by said movement, a trip for releasing said latch, a stepped lever for positioning said trip, a series of lugs on certain of said counter stops acting to move said stepped lever different amounts when certain of the tabulating keys are actuated, said column 20 stops having shoulders of graded magnitudes to coöperate in order with said trip in the successive positions thereof, said column stops acting to depress said trip to release said latch, enabling said spring to move 25 the connected counter stop into the path of the column stop actuating the trip.

14. The combination with a carriage, a series of column stops for said carriage, a plurality of counter stops coöperating with 30 said column stops, tabulating keys for actuating said counter stops, a control key for determining the effective relation of the two sets of stops, a plunger actuated by said control key, a bell crank actuated by said 35 plunger, a rod connected to said bell crank, all but one of said counter stops having openings therethrough, through which said rod extends, a latch connected to said bell crank to move the remaining one of said 40 counter stops, a spring tensioned by the movement of said remaining counter stop, so as to tend to return it to its normal position, a trip for releasing the latch, and selective means controlled by certain of said 45 tabulating keys for determining the extent of actuation of said trip to correspond with different columns.

15. The combination with a carriage, of a series of column stops, a series of plungers 50 to coöperate with said column stops to determine the position of said carriage, a trip coöperating with said column stops to determine the position of said carriage, tabulating keys for actuating said column stops 55 and said trip, said plungers and said trip being alternative in their effectiveness, and means for determining whether said plungers or said trip shall be effective.

16. The combination with a carriage, of 60 a series of column stops for said carriage,

counter stops to coöperate with said column stops for controlling the position of said carriage, a trip to coöperate with said column stops to control the position of said carriage, a stepped lever for determining the relative position of said trip with respect to said column stops, said column stops being of different forms to correspond with the different positions of said trip, lugs carried by certain of said counter stops, said stepped lever being in the path of said lugs, whereby the actuation of the lug-carrying counter stops will position said trip, and a series of tabulating keys for actuating said counter stops.

17. The combination with a carriage, of a series of column stops for said carriage, counter stops to coöperate with said column stops for controlling the position of said carriage, a trip to coöperate with said column stops to control the position of said carriage, a stepped lever for determining the relative position of said trip with respect to said column stops, said column stops being of different forms to correspond with the different positions of said trip, lugs carried by certain of said counter stops, said stepped lever being in the path of said lugs, whereby the actuation of the lug-carrying counter stops will position said trip, a series of tabulating keys for actuating said counter stops, and means for concomitantly rendering said counter stops ineffective, and said trip effective.

18. The combination with a carriage, of a series of column stops for said carriage, counter stops to coöperate with said column stops for controlling the position of said carriage, a trip to coöperate with said column stops to control the position of said carriage, a stepped lever for determining the relative position of said trip with respect to said column stops, said column stops being of different forms to correspond with the different positions of said trip, lugs carried by certain of said counter stops, said stepped lever being positioned to coöperate with said lugs, whereby the actuation of the lug-carrying counter stops will position said trip, and a series of tabulating keys for actuating said counter stops, said lugs each having a cut-out portion to permit the free movement of said counter stops without actuating said stepped lever when said counter stops are themselves effective.

19. The combination with a carriage, of a series of stops, a second series of stops coöperating with said first-mentioned stops to determine the position of said carriage, tabulating keys for actuating said stops, a special control key for rendering said stops ineffective, a trip to release one of said stops, and means to enable said control key to render said trip effective.

20. The combination with a carriage, of

a series of column stops for said carriage, a series of counter stops coöperating with said column stops to determine the position of said carriage, tabulating keys for actuating 5 said column stops, a trip movable into the path of said column stops to bring one of said counter stops into the path of one of said column stops, lugs on certain of said counter stops spaced apart at their upper 10 surfaces to form cut-out portions, a lever

for shifting said trip normally located above said cut-out portions, so as to be unaffected by said counter stops, and a key for moving said counter stops to an ineffective position and at the same time bringing said lugs in 15 effective relation with said lever.

WALTER E. BARNARD.
